ROUND PANEL LAMP

Gene I. Thomasson, Wickliffe, Ohio, assignor to General Electric Company, a corporation of New York

Filed Nov. 15, 1960, Ser. No. 62,855

Term of patent 14 years

(Cl. D48—23)

FIG. 1 is a bottom plan view of a round panel lamp showing my new design.

FIG. 2 is a reduced top plan view thereof.

FIG. 3 is a fragmentary sectional view looking in the direction of the arrows 3—3 of FIG. 1.

FIG. 4 is a fragmentary elevation thereof looking in the direction of the arrows 4—4 of FIG. 1.

FIG. 5 is a fragmentary elevation thereof looking in the direction of the arrows 5—5 of FIG. 1.

The dominant features of my new design are shown in solid lines with shading in the drawing. The lining on the embossed lens members in FIG. 1 represents contour shading.

I claim:

The ornamental design for a round panel lamp, as shown and described.
